UNITED STATES PATENT OFFICE

SAMUEL R. MCCLAY, OF CANTON, OHIO

SPRING EQUALIZER

Application filed March 28, 1928. Serial No. 265,400.

The invention relates to a spring balancing device adapted to be attached to a pump for counterbalancing the pump rod, and is applicable to both hand operated and power 5 pumps.

It is well known that in the operation of a pump the load is much greater on the up stroke of the pump rod than on the down stroke thereof, as the up stroke requires power to lift the weight of the rod together with the weight of the water lifted. There is also some friction of the water and as water is often pumped against considerable pressure this increases the load on the up stroke of the 15 rod while the down stroke has practically no load to lift.

The present invention contemplates the provision of a spring equalizer by means of which the load upon the pump rod will be 20 substantially equalized, whereby it will require practically the same amount of power on the down stroke which it does on the up stroke, thus materially reducing the power and producing a smoother operating pump.

25 The objects of the improvement are to provide an equalizer for deep well pumps which will assist in raising the pump rod and the water raised thereby; to provide for an equalization of the lifting and return 30 strokes; to prevent pounding of the pump rod; and to provide a spring equalizer which is practical, efficient, durable, inexpensive to manufacture, and easily applied to the pump.

An embodiment of the invention is illustrated 35 in the accompanying drawings in which the improved equalizer is shown for the purpose of illustration as applied to a power pump, in which

Figure 1 is a perspective view of a pump 40 showing the improved equalizer applied to the pump rod thereof;

Fig. 2, an elevation of the equalizer; and

Fig. 3, an enlarged sectional view of the 45 central guide for the springs.

Similar numerals refer to similar parts throughout the drawings.

A power pump of any usual and well known design is shown generally at 1 provided 50 with the motor 2 arranged to recipro-

cate the arm 3 in the slot 4 in customary manner.

The usual pump rod 5 is connected to the vertically moving arm 3 in any usual and well known manner, whereby this rod is continuously reciprocated vertically during the 55 operation of the pump.

The improved equalizer to which the invention pertains may be carried by a base 6 and is provided with the rod 7 slidably 60 mounted through said base and adapted to be connected in any suitable manner to the pump rod 5. It should be noted that this rod 7 may, if desired, be a continuation of the pump rod 5, but in order to adapt the 65 equalizer to standard pumps now in use a suitable connection may be provided between the rod 7 and the pump rod.

This connection may comprise a block 8 having horizontal and vertically disposed 70 bifurcations 9 and 10, respectively, for connection to the arm 3 of the pump, whereby the rod 7 will be reciprocated with the pump rod.

Two or more coil springs 11 are located 75 around and spaced from the rod 7 in alignment with each other. The lower spring has its lower end portion located around a guide boss 12 upon the upper side of the base 6, said boss being substantially the inner diameter of the spring.

The upper end of the upper spring is located around a guide boss 13 upon the collar 14 against which this spring bears. This collar is held against upward movement on 85 the rod as by a nut 15 located upon the upper threaded end 16 of the rod.

Each of the springs 11 may be of substantially equal length and a central bearing guide 17 is preferably interposed upon 90 the rod 7, between the lower end of the upper spring and the upper end of the lower spring.

This bearing guide is provided with the upper and lower guide bosses 18 and 19, respectively, around which the adjacent end 95 portions of the springs are located. In order to provide for greater bearing surface upon the rod 7, bearing bosses 20 may be provided at the upper and lower ends of this member.

For the purpose of keeping this central 100

guide lubricated, the same may be provided with a chamber 21 surrounding the rod and adapted to be packed with felt or the like as shown at 22 an oil hole 23 communicating therewith for the purpose of lubricating the same from time to time.

In order to easily and readily attach the equalizer to a power pump, such as illustrated, a pair of depending pipes 24 may be 10 carried by the base 6, the lower ends thereof being adapted to be seated over the nuts 25 which are usually provided upon pumps of this character. The pressure of the springs 11 against the base 6 will hold the pipes upon 15 these nuts and prevent accidental displacement of the equalizer.

By connecting the rod 7 to the pump rod as by the block 8, above described, side movement of the equalizer is also prevented. The 20 equalizer is thus held in perfect vertical alinement with the pump rod and may thus be easily and quickly installed upon an electric power pump such as illustrated.

The fact that the rod 7 is thus connected 25 to the pump rod and is slidably located through a guide in the base 6 together with the spring tension upon the base at all times, makes it impossible for the equalizer to get 30 out of place once it is installed as illustrated and described.

The bearing guide 17 equalizes the tension of the two springs 11 and travels up and down upon the rod 7 in positive alinement therewith. The guide bosses upon this bearing guide, as well as the bosses 12 and 13 35 upon the base and collar 14, holds the springs in perfect alinement and prevents the same from buckling.

By providing the elongated threaded 40 tension 16 upon the upper end of the rod 7 with the nut 15 and jamb nut 26, permits for adjustment of the position of the collar 14, thereby adjusting the tension upon the springs 11 to accommodate the particular 45 pump to which the equalizer is applied, thus permitting the same to be adjusted to its highest point of efficiency and permitting the same to be easily adjusted equally to accommodate deep or shallow wells as desired.

It is, of course, understood that power 50 pumps ordinarily range from a six inch stroke to as high as a twenty-four or even thirty inch stroke. To accommodate pumps having the longer range of stroke, it will be necessary 55 to increase the number of springs accordingly and to provide additional guides, such as 17, between the springs.

The equalizer illustrated is adapted for 60 a pump having a six inch stroke. The springs 11 should each be substantially ten inches long and about two and one-eighth inches in diameter. The combined compression of 65 these springs is about twelve inches, about half of which may be efficiently used as a working capacity, the balance being needed

for adjusting the equalizer to attain the highest efficiency.

As the length of the stroke of the pump is increased the number of springs should be increased accordingly, maintaining however 70 the same proportions as to the size of the springs and the amount of compression to be utilized as a working capacity of the device.

By maintaining this relative size of spring and providing the sliding guide 17 between 75 each pair of springs, buckling of the springs is prevented. The springs are thus kept away from the rod preventing friction and wear on the springs which would be the occasion thereby.

From the above it will be evident that the 80 co-operation of the springs 11 with the guide 17 will counterbalance the weight of the pump rod and the water lifted thereby, thus materially reducing the power required to operate the pump; and the constant spring tension on the pump rod will equalize the up stroke and down stroke of the rod and will prevent pounding of the rod and produce a 85 smooth even stroke.

Although the invention is illustrated and described as applied to a power pump, it should be understood that the improved equalizer may be applied to a hand operated pump to which it is equally adaptable with- 90 out any change in the invention.

It should be understood that the sliding guide 17 is necessary in order to prevent buckling of the springs. If only a single spring of the combined length of the two springs 11, 100 105 were used, the length of the spring would cause the same to buckle under tension and to contact with the rod, preventing efficient operation of the device.

But by forming the springs of short length, 110 as shown and interposing the sliding guide between the ends of the springs and having the guide bosses 18 thereon, buckling of the springs is absolutely prevented.

I claim:

1. An equalizer for pumps including a base, a rod slidably mounted through the base and adapted to be connected to the pump rod, a guide boss upon the base surrounding the rod, a collar at the upper end portion of the rod, a guide boss upon said collar surrounding the rod, a coil spring around the rod having its lower end surrounding the guide boss upon the base, a second spring in alinement with the first spring having its upper end surrounding the guide boss on the collar, and a guide bearing slidably mounted upon the rod between said springs and provided with guide bosses receiving the adjacent ends of the springs.

2. An equalizer for pumps including a base, a rod slidably mounted through the base and adapted to be connected to the pump rod, a guide boss upon the base surrounding 130

the rod, a collar at the upper end portion of the rod, means for adjusting said collar longitudinally upon the rod, a guide boss upon said collar surrounding the rod, a coil spring

tension of the springs upon the base holds the equalizer in position upon the pump.

In testimony that I claim the above, I have hereunto subscribed my name.

SAMUEL R. McCCLAY. 70

- 5 around the rod having its lower end surrounding the guide boss upon the base, a second spring in alinement with the first spring having its upper end surrounding the guide boss on the collar, and a guide
 10 bearing slidably mounted upon the rod between said springs and provided with guide bosses receiving the adjacent ends of the springs.

75

3. An equalizer for pumps including a
 15 base, a rod slidably mounted through the base and adapted to be connected to the pump rod, a guide boss upon the base surrounding the rod, a collar at the upper end portion of the rod, a guide boss upon said collar surrounding the rod, a coil spring around the rod having its lower end surrounding the guide boss upon the base, a second spring in alinement with the first spring having its upper end surrounding the guide boss on the
 20 collar, a guide bearing slidably mounted upon the rod between said springs and provided with guide bosses receiving the adjacent ends of the springs, and bearing bosses upon the base, collar and guide bearing for increasing the bearing surface for the rod.

80

4. An equalizer for pumps including a base, a rod slidably mounted through the base and adapted to be connected to the pump rod, a guide boss upon the base surrounding the rod, a collar at the upper end portion of the rod, a guide boss upon said collar surrounding the rod, a coil spring around the rod having its lower end surrounding the guide boss upon the base, a second spring in alinement with the first spring having its upper end surrounding the guide boss on the collar, a guide bearing slidably mounted upon the rod between said springs and provided with guide bosses receiving the adjacent ends of the springs, and a lubricating chamber in the guide bearing, surrounding the rod.

85

5. An equalizer for pumps including a base, a rod slidably mounted through the base and adapted to be connected to the pump rod, a guide boss upon the base surrounding the rod, a collar at the upper end portion of the rod, a guide boss upon said collar surrounding the rod, a coil spring around the rod having its lower end surrounding the guide boss upon the base, a second spring in alinement with the first spring having its upper end surrounding the guide boss on the collar, a guide bearing slidably mounted upon the rod between said springs and provided with guide bosses receiving the adjacent ends of the springs, and tubes depending from the base and adapted to be placed over nuts and the like upon the pump, whereby the
